UNITED STATES PATENT OFFICE.

WATSON F. HAMMOND, OF MASHPEE, MASSACHUSETTS.

CRANBERRY-SCREEN.

SPECIFICATION forming part of Letters Patent No. 280,872, dated July 3, 1883.

Application filed October 13, 1882. (No model.)

To all whom it may concern:

Be it known that I, WATSON F. HAMMOND, of Mashpee, in the county of Barnstable and State of Massachusetts, have invented a new 5 and Improved Cranberry-Screen, of which the following is a full, clear, and exact description.

My invention consists of a hopper, platform, screen-grate, discharging-spout, and feeding contrivances, constructed and arranged, as 10 hereinafter described and claimed, to facilitate the screening of cranberries preparatory to packing them in barrels for market, all as hereinafter described.

Reference is to be had to the accompanying 15 drawings, forming part of this specification, in which similar letters of reference indicate corresponding parts in all the figures.

Figure 1 is a perspective view of a cranberry-screen constructed in accordance with my im- 20 provements. Fig. 2 is a sectional elevation through the hopper and screen. Fig. 3 is a detail in side elevation. Fig. 4 is a detail of the jarring device employed to aid in feeding the cranberries, the same being in horizontal 25 section of part of the hopper.

I make a hopper, *a*, to contain the berries to be screened, the said hopper having a slanting bottom, *b*, with a drop-gate, *c*, below the bottom, for allowing the berries to escape; and 30 over the falling edge of the gate is a sliding board, *d*, to be employed for jarring the hopper to cause the berries to run out in batches, as wanted from time to time. The gate *c* is hinged to the bottom *b* at *e*, and is fastened up 35 to the jar *d* by a strap or hasp, *f*, and pin *g* when the hopper is to be closed. The board *d* is fixed in slots *i* of the end boards, *j*, of the hopper, to slide forward and backward there- 40 in, and has a spring, *k*, to thrust it forward and cause a jar by the cleat *l*, attached to it, striking the end of the hopper after the board 45 has been pulled back by the finger of the attendant applied to the cleat *m*.

The screen-grate *n* is located in the base or 45 platform *o* of the machine, in advance of the hopper, suitably for the batches of berries to be spread out over it by the attendant for screening them preparatory to shoving them off through the spout *p* *q* into the barrel or 50 other receptacle for them. The end section, *q*, of the spout-bottom is provided with flange

q', and is jointed to the rest at *s*, so that it can be turned over upon the part *p*, next to the screen, for a stop to prevent berries and other matters from escaping before they are 55 sufficiently screened, said section being turned up, as in Fig. 2, when serving to stop the escape, and down, as in Fig. 1, to allow the escape of the berries.

For enabling the hopper to be taken off of 60 the platform to be filled, it is detachably connected thereto by means of the grooved cleats *t*, attached to the edges of the platform, and cleats *u*, attached to the ends of the hopper, enabling the hopper to be readily connected 65 and disconnected by sliding out and in the grooves of cleats *t* from the back of the platform.

The platform *o* is designed to be set up on any suitable support at the back, with the 70 spout end resting on the top of the barrel, box, or other receptacle for the berries, so that they will discharge from the spout into said receptacle.

The hopper has cleats *w*, attached to the up- 75 per edges of the ends *j*, for handles, by which to lift it when removing it from the platform to be filled and replacing it again, and when so filled and in position the strap or hasp *f* is lifted from pin *g* and the hinged bottom *c* 80 opened, whereupon the jar *d* may be operated, as above described, to cause a moderate amount of berries to fall from the hopper at each movement of the jar *d* upon the screen *n*, to be as- 85 sorted and discharged.

Having thus fully described my invention, what I claim as new, and desire to secure by Letters Patent, is—

1. The combination, with the platform *o* and grate *n*, of the hopper *a*, provided with drop- 90 gate *c* and the jarring-board *d*, substantially as described.

2. The grate *n*, provided with the spout *p* *q*, the part *q* being provided with the flange *q'* and hinged to the part *p*, and adapted to be 95 turned over upon said part *p* to form a stop, substantially as and for the purpose set forth.

3. The combination of hopper *a*, having drop-gate *c* and jarring-board *d*, with the platform *o* and grate *n*, said hopper and platform 100 being detachably connected together, substantially as described.

4. The sliding board *d*, having cleats *l* and *m* and spring *k*, in combination with hopper *a* and grate *n*, substantially as described.
5. The combination, with the hopper *a*, having a slanting bottom, *b*, and the jarring-board *d*, of the drop-gate *c*, hinged to the slanting bottom and held against the lower edge of said jarring-board, substantially as herein shown and described.

WATSON F. HAMMOND.
